The ornamental design for a display panel for display of fantasy sports player transaction data, as shown and described.

DESCRIPTION

FIG. 1 illustrates a display panel for display of fantasy sports player transaction data according to the first embodiment of the invention; and,

FIG. 2 illustrates a display panel for display of fantasy sports player transaction data according to the second embodiment of the invention.

The outer solid line in all figures illustrates the display panel in which the fantasy sports transaction data is embodied. The perimeters of the display panel and the fantasy sports transaction data are understood to be flush. The text and chart elements shown in broken lines in all figures form no part of the claimed design.
